KERF-CUTTING MINING MACHINE

Edward H. Stein, Columbus, Ohio, assignor to
 The Jeffrey Manufacturing Company, a corpora-
 tion of Ohio

Application November 27, 1946, Serial No. 712,673

2 Claims. (Cl. 262—28)

1

My invention relates to kerf-cutting mining machines and more particularly to a mining machine wherein a kerf-cutter is mounted upon a support for rotational movement.

It is an object of my invention to provide an improved kerf-cutting mining machine wherein a supporting vehicle carries a kerf-cutter head mechanism and reversible hydraulic motor means therefor in cantilever through a turnover neck mechanism having a hydraulic pump associated therewith connected to supply hydraulic fluid to the hydraulic motor means through conduits which are formed at least in part by co-operating supporting rotary connecting members of the turnover neck mechanism and which may include valve means for reversing the direction of operation of the hydraulic motor means.

It is another object of my invention to provide an improved kerf-cutting mining machine wherein a kerf-cutter head mechanism having hydraulic motor means associated therewith is supported in cantilever through a turnover neck mechanism from a support wherein a hydraulic pump carried by the support is connected to the hydraulic motor means through conduits formed at least in part by co-operating supporting rotary connecting members of the turnover neck mechanism.

It is another object of my invention to provide an improved turnover kerf-cutter head supporting mechanism wherein a kerf-cutter head carrying member is connected and supported from a support member solely through a male and a female member that co-operate to provide rotary motion of the kerf-cutter head supporting member about the axis of the male member and to form connecting hydraulic conduits that remain in constant communication irrespective of the rotary position or motion of the co-operating male and female members and which extend through at least one of the tines of the yoke to adjacent the outer end thereof through which hydraulic fluid may be conducted for operating the kerf-cutter head.

It is another object of my invention to provide an improved kerf-cutter head mechanism in which an endless kerf-cutter chain is driven by rotary hydraulic motor means carried by the cutter head.

It is another object of my invention to provide an improved kerf-cutter head mechanism having a frame that carries rotary hydraulic motor means and a cutter bar and chain assembly and wherein the rotary hydraulic motor means is connected to drive the kerf-cutter chain.

2

It is still another object of my invention to provide an improved kerf-cutter driving head mechanism having a frame carrying a reduction gear mechanism adapted to drive an endless kerf-cutter chain and supporting a pair of rotary hydraulic motors both of which drive the same gear of the speed reduction gear mechanism.

Other objects of the invention will appear hereinafter the novel features and combinations 10 being set forth in the appended claims.

In the accompanying drawings,

Fig. 1 is a side view in elevation of a mining machine that includes my invention with parts omitted for the sake of clarity;

15 Fig. 2 is a plan view of the forward portion of the mining machine shown in Fig. 1 with a portion of the cutter head housing broken away and a sump cover removed;

Fig. 3 is a view of the bottom of the cutter 20 head and cutter head supporting neck of the mining machine shown in Fig. 1 with parts omitted for the sake of clarity;

Fig. 4 is a view in section of the cutter head 25 mechanism, the view being taken on line 4—4 of Fig. 3;

Fig. 5 is an elevational sectional view taken through the cutter head supporting neck mechanism and a pump housing of the mining machine, the view being taken on line 5—5 of Fig. 2;

30 Fig. 6 is a sectional elevational view taken substantially on line 6—6 of Fig. 5;

Fig. 7 is a sectional elevational view through the cutter head supporting neck mechanism of the mining machine with parts of a housing structure broken away to show the cutter head 35 turnover gearing, the section being taken on line 7—7 of Fig. 5;

Fig. 8 is a view in section through the cutter 40 head supporting neck mechanism and the cutter head leveling cylinder of the mining machine, the view being taken on line 8—8 of Fig. 5;

Fig. 9 is a view similar to Fig. 3, but on a larger scale and showing hydraulic pipes in the turnover neck mechanism that lead to the hydraulic 45 motors of the cutter head;

Fig. 10 is a diagrammatic illustration of the 50 hydraulic control system of the mining machine; and

Fig. 11 is a diagrammatic sectional elevational 55 view of a reversing valve embodied in the hydraulic control system.

Referring specifically to Figs. 1 and 2 of the drawings, there is shown a kerf-cutting mining machine including a vehicle or truck 10 having a forward axle 11 and a rear axle 12 to which there

are keyed flanged track engaging wheels 13 adapted to ride on track rails 14. Truck 10 includes a rear machinery containing housing 15 which houses an electric motor, hydraulic pumps, valves, and other mechanisms, some of which are indicated diagrammatically in Fig. 10, and most of which mechanisms function to swing and position a kerf-cutter bar assembly 16 of a kerf-cutter head 17. The truck 10 and the machinery contained in the compartment 15 is identical to that disclosed in United States Patent No. 2,263,799 to Robert K. Jeffrey and Lewis E. Mitchell, entitled "Mining Machine." While I prefer this track mounted type of truck or vehicle, the said truck may be mounted in any other desired manner such, for example, as upon endless treads to operate in a trackless mine room, as illustrated in U. S. Patent 2,357,724 to J. S. Beltz.

Mounted upon the truck 10 for swinging movement in a horizontal plane or about a central upright axis is a turntable 18. Turntable 18 is rotated about its central upright axis by a pair of piston motors 19 (seen in Fig. 2) that are always operated together and in reverse directions so that a very powerful and equalizing force will be transmitted to turntable 18 to swing it. Turntable 18 includes a pair of upwardly extending brackets 20 between which is mounted a motor housing or casing 21 that forms the rear end of an elongated generally horizontal supplemental frame or support supported by the truck 10 within which casing 21 there is an electric motor having an armature shaft 22 (see Fig. 6) the pinion 23 of which drives a gear 24 on the shaft of a hydraulic pump 25 mounted within a casing, housing or sump 26 secured by bolts 27 to the forward end of the motor housing 21 and carried in cantilever by the latter. To each side of the motor housing 21 and housing 26 is a supporting arm 28 connected at one end to the housing 26 by bolts 29 and the opposite end of each of which forms a bearing portion 30 positioned to the outside of one of the upright supporting brackets 20 of turntable 18. Pivot shafts 31 extend through the bearing portion 30 of arms 28, brackets 20 and into bearing sockets formed in the sides of the motor housing or support 21 for mounting the housings 21 and 26 to the turntable 18 for pivotal movement above the horizontal axis of the aligned pivot shafts 31. Between each of the arms 28 and the motor housing 21 is a double acting piston type hydraulic motor 32 mounted by trunnions 33 that fit in bearing sockets formed in the arms 28 and the motor housing 21 and these hydraulic motors 32 function to raise and lower the housings or supplemental frames 21 and 26 pivotally about the horizontal axis of the pivot shafts 31.

Extending from the forward end of the casing, housing or sump 26 and supported in cantilever thereby is a turnover neck mechanism indicated generally at 34 which pivotally supports the hydraulically powered cutter head mechanism 17 at its outer end. Said sump 26 and neck mechanism 34 form parts of the above mentioned supplemental frame. The turnover neck mechanism 34 is rotated about its longitudinal axis by a reversible rotary hydraulic motor 35. Hydraulic motors 19, 32 and 35 are operated by a hydraulic pump 392 and other mechanism in the machine compartment 15. Cutter head 17 is carried between a pair of forwardly extending tines or arms 36 of turnover neck mechanism 34 (forming part of the supplemental frame) for pivotal movement with respect thereto about a swingable axis trans-

verse to the longitudinal axis of the supplemental frame 26 and the cutter bar assembly 16 of the cutter head 17 may be rotated about an axis extending through the cutter head 17 and at right angles to said transverse axis by a reversible rotary type hydraulic motor 37.

From the foregoing it is obvious that the cutter head mechanism 17 and its associated kerf-cutter bar assembly 16 are mounted in cantilever on the front or forward end of an elongated generally horizontal frame made up of parts 21, 26, 34, etc., the rear end of which is supported by the main frame 10 through turntable 18 and that the kerf-cutter bar assembly 16 is mounted through the turnover neck and its associated members for universal movement, that is, movement about a plurality of right angle axes, namely, the vertical axis through the turntable 18, the horizontal axis of pivot shafts 31, the longitudinal axis of the turnover neck mechanism 34, an axis extending crosswise of the tines or arms 36, and the kerf-cutter bar assembly 16 is itself pivotal about an axis extending through the cutter head mechanism 17. Thus the cutter bar assembly is mounted for universal movement with respect to the supporting vehicle or truck 10 for cutting a kerf in substantially any plane.

Referring now to Fig. 5, which is a view in section of a portion of the turnover neck mechanism 34 and the casing, housing or sump 26, the turnover neck mechanism 34 includes means to provide conduits from pumps 25 and 392 to hydraulic motors on head 17 which provide for continuous unrestricted rotation of said head on the longitudinal axis of said supplemental frame. Said turnover head mechanism includes a stub shaft or projecting male member 38 which is formed as a part of the casting 39 that forms the bottom of the casing, housing or sump 26 within which the hydraulic pump 25 is contained. The stub shaft 38 adjacent the forward wall or end of the casting 39 is provided with a circular flange 40 and a rear bearing surface 41. The body of the shaft 38 extends forwardly from adjacent the bearing surface 41 and is provided at its forward end with a bearing surface 42. Between bearing surfaces 41 and 42 and on the outer surface of shaft 38 there is a plurality of circular peripheral grooves 43 between which the shaft body is provided with suitable oil sealing rings, such as O-rings, in grooves 44. Stub shaft 38 is bored or has formed integral therewith a plurality of conduits 45 (see Figs. 6, 7, 9 and 10) which extend longitudinally therein and through the forward wall of the casting 39. Each of the conduits 45 at its outer end is connected to a separate one of the circular grooves 43 through a radial conduit or bore 46. The purpose of these conduits will be fully described hereinafter.

Telescoped over the stub shaft or protruding male member 38 is a tubular or female neck member or frame 47 the rear end of which contains a bushing adapted to bear upon the bearing surface 41 and the front end of which contains a bushing adapted to bear on the bearing surface 42. Bore 48 of the female neck member 47 forms a close fit with the lands of the grooved portion of the stub shaft 38 and oil sealing rings 44 bear upon the bore 48 to prevent loss of hydraulic fluid from grooves 43. Each groove 43 communicates with a radially extending conduit in female member 47 (see Figs. 8 and 10). Each groove 43 is closed by an adjacent surface portion of the interior of female member 47. The rear end of the female neck member 47 is flanged

at 49 to carry a split worm gear 50. Gear 50 overlaps and engages the circular flange 48 preventing endwise movement of the co-operating rotary male and female members 38 and 47. Preferably the outermost end of the stub shaft 38 has secured thereto a cap 51 also for the purpose of preventing endwise movement of the co-operating members 38 and 47. Male member 38 and female member 47 therefore cooperate to provide support of the latter, and in turn the kerf cutting mechanism, from the former, and also cooperate to provide continuous conduits leading to hydraulic motors 37, 57 and 67 while providing for continuous unrestricted rotation of the head 17 along the axis of said stub shaft 38 and female member 47.

As seen in Fig. 7, split worm gear 50 is secured to flange 49 of female neck member 47 by a series of bolts 52 and it is driven by an engaging driving worm 53 driven by rotary hydraulic motor 35 through suitable reduction gearing contained within gear housing 54. It will be seen that when rotary hydraulic motor 35 is driven in either direction the split worm gear 50 will be rotated and it will rotate the female neck member 47 upon the stub shaft 38 about the axis of the latter. Preferably the split worm gear 50 is covered by a split housing 55 which is clamped to a flange 56 at the forward end of the casting 39 of casing, housing or sump 26.

The female neck member 47 of turnover neck mechanism 34 is forked to form a yoke at its forward end to which forwardly extending tines or arms 36 are rigidly secured, by bolts or the like, and between which is mounted the hydraulically powered cutter head 17. Hydraulically powered cutter head 17 has associated with it four hydraulic motors, one of which is a piston type motor 57 mounted to a surface 58 formed on the female neck member 47. Piston rod 59 of motor 57 is connected through a connecting link 60 to an arm 61 formed integral with the frame or housing 62 of cutter head 17 and this motor functions to rotate the cutter head 17 and its associated kerf-cutter bar 16 about the transverse axis of mounting pins 63 (see Figs. 1 and 9) which are carried in aligned openings formed adjacent the outermost end of each of the tines or arms 36. Each pin 63 is formed as a sidewardly projecting part of one of a pair of upstanding lugs 64 that are integral parts of the housing or casing 62.

Referring now to the novel construction of the cutter head mechanism, the cutter head mechanism 17 includes a frame or housing 62 which, as seen in Fig. 4, is formed of an upper casting 65 which has a pair of housings 66 formed integral with it for enclosing reversible rotary hydraulic motors 67. Each motor 67 includes a downwardly extending main shaft 68 that operates in upper and lower bearings 69 and 69' and carries a pinion 70. Frame or housing 62 includes a bottom or lower casting 71 which co-operates with the upper casting 65 to form a gear casing which houses the pinions 70 of hydraulic motors 67 and a central main shaft 72 carried in bearings 73 and 73' in the upper and lower castings. Shaft 72 extends through the bottom casting 71 and through a labyrinth type lubricant seal formed by a plate 74 attached to the bottom casting. A sprocket 75 carried upon the end of shaft 72 is adapted to drive an endless kerf-cutter chain 76 carried by the frame of cutter bar 16, links of which are indicated only in Fig. 2. Housing 62 above central main

shaft 72 is closed by a suitable dust cap 77. Central main shaft 72 carries a relatively large gear 77 which is directly engaged and driven by the pinions 70 of both reversible rotary hydraulic motors 67. It will be seen that the pinions 70 each mesh with the large gear 77 which drives central main shaft 72 and that pinions 70 and gear 77 form a speed reducing or torque increasing gearing contained within the cutter head 17 that directly connects the hydraulic motors 67 to the sprocket 75 for driving the kerf-cutter chain 76.

Lower casting 71 includes a boss 78 which carries a cutter bar supporting ring 79 through a bushing 80. Cutter bar assembly 16 is secured to a foot or lug 81 of this ring member by stud bolts 82. The upper surface of the cutter bar supporting ring member 79 is circumferentially notched at its outer periphery 83 to receive a ring gear 84 secured thereto for rotating the supporting ring member 79 by a plurality of bolts 85 which extend through aligned openings in ring member 79, ring gear 84 and are threaded into a ring 86 to form an assembly thereof which engages a circumferential supporting shoulder 87 formed by the bottom casting 71. A flange 88 including a sealing ring 89 closely fits the outer peripheral edge of the cutter bar supporting ring member 79 and is bolted to the upper casting 65 of the frame or housing 62. The chief function of flange 88 and sealing ring 89 is to protect the ring gear 84.

Frame or housing 62 of cutter head 17 includes a projected portion 90 (see Fig. 2) which contains a worm 91 driven through reduction gear mechanism 92 from reversible hydraulic motor 37. It will be seen that when hydraulic motor 37 is operated in either direction, worm 91 will rotate the cutter bar supporting ring member 79 through ring gear 84 about the axis of shaft 72.

The general plan of utilizing a reversible rotary hydraulic motor carried directly by the cutter head 17 for swinging the cutter bar 16 as described, is the invention of Arthur L. Lee and is described in his application, Serial No. 22,268, filed April 21, 1948, for a Kerf-Cutting Mining Machine.

Referring now to Figs. 9 and 10 wherein the hydraulic conduits leading to motors 37 and 67 are shown, the hydraulic motors 67, which are reversible, form the sole final power means for directly driving the kerf-cutter chain 76 and they are provided with inlet and outlet ports connected in parallel by pipes or conduits 93 and 94. Conduits 93 and 94 are reversibly connected, as more fully described hereinafter, to the pump 25 and sump 26 so that when fluid is supplied by pump 25 to one of the pipes, both of the motors 67 will rotate in the same direction and the other pipe will convey fluid exhausted from the motors to sump 26. Connected to pipe 93 is a flexible conduit 95 (see Fig. 9) which in turn is connected to a conduit 96 formed in one of the pins 63. Conduit 96 leads to inner circumferential groove 97 in the pin 63 which in turn connects with a conduit 98 that extends longitudinally through an arm or tine 36 of the turnover neck 34 and is connected to a conduit 99 formed in an arm 100 of the yoke of female member 47. Conduit 99 communicates with one of the circumferential grooves 43 formed in the projecting stub shaft 38 and, as previously described, each of the grooves 43 is connected through a radial conduit 46 (see Fig. 8) to a longitudinal conduit 45 in the stub shaft 38. Preferably a suitable

sealing ring or gasket 101 (see Fig. 9) is provided at the junction of the arms or tines 36 and arm 100 to prevent loss of hydraulic fluid where the conduits 98 and 99 join. Pipe 94 is connected to the conduit 96 in the other pin 63 through a flexible conduit, and conduits corresponding to those described are provided in the other arms 36 and 100 for connecting the conduit 96 to another of the grooves 43 and to one of the conduits 45. As clearly shown in Figs. 6 and 10, the two conduits 45 which are individual to the pipes 93 and 94, respectively, are coupled directly to the output ports 111 and 110, respectively, of reversing valve 105 hereinafter described in detail. As suggested in Fig. 5, other conduits 45 are connected to valve 448 (see Figs. 6 and 10) by flexible conduits, including conduits 362 and 363, and appropriate fittings. It will be seen that the pipes 93 and 94 are in constant communication with their respective conduits 45 in the stub shaft or protruding male member 38 irrespective of the rotary position or rotation of the female member 41. It will also be seen that the co-operating rotatable male and female members of the turnover neck mechanism 34 form a supporting means for supporting the hydraulically powered cutter head mechanism 17 and its associated cutter head 16 in cantilever and that the male and female members co-operate to form conduits through which hydraulic fluid is fed to and exhausted from the hydraulic motors 67 even when the female member 41 is continuously rotated by motor 35.

Rotary hydraulic motor 37 is connected by conduits 102 and 103 (see Fig. 9) with a pair of conduits 45 through the turnover neck mechanism that are similar to those conduits described that connect conduit 93 with one conduit 45 and thus hydraulic fluid for motor 37 as well as motors 67 is conducted through the turnover neck mechanism 34. The conduits for motor 37 include the outer grooves in pins 63 (see Figs. 9 and 10), and lead ultimately to conduits 362, 363 through conduits 45 individual thereto. Motor 37 therefore is energized from pump 392, as hereinafter described. Individual conduits 45 for cutter bar tilting piston motor 57 also extend through said neck mechanism.

Sump housing 26 contains a supply of hydraulic fluid that is pumped by pump 25 for operating the hydraulic motors 67 that drive the kerf-cutter chain 16 of kerf-cutter head 17. Pump 25 is contained within sump 26 and its outlet or discharge port is connected through a pipe 104 to the inlet port of a reversing valve 105, the actuating shaft 106 of which extends through a suitable stuffing box 107 (see Fig. 6) in the wall of the sump casting 39 to a suitable motion changing device 108 which is actuated by a rod 109 connected to a manually controlled member, not shown, positioned adjacent the rear of the motor casing 21. The reversing valve 105 is indicated diagrammatically in cross section in Fig. 11 and it includes a motor port 110 and motor port 111 each connected to one of the conduits 45 in the turnover neck mechanism 34 that lead to pipes 93 and 94. Reversing valve 105 also includes two discharge ports 112 and 113 through which fluid being returned from the motors 67 or by-passing them, as the case may be, is exhausted to sump 26.

In operation, with the piston or core 115 of valve 105 in the position shown in Fig. 11, hydraulic fluid flowing from pump 25 enters inlet port of valve 105 from pipe 104 and flows through

grooves, notches or slots 114 in piston or core 115 to both of the ports 110 and 111. Because fluid then flows to both pipes 93 and 94 the motors 67 will not be operated and the fluid will be caused to flow in ports 110 and 111 through grooves, notches or slots 116 in core 115 to exhaust ports 112 and 113 and to sump 26. However, when the core 115 is moved to the left, as seen in Fig. 11, a land 117 of the core is moved to stop the flow of fluid from inlet port 104 to discharge port 110 and a land 118 of core 115 is moved to stop the flow of fluid to outlet port 112. With the core 115 in this position, hydraulic fluid entering port 104 flows to port 111 and to the hydraulic motors 67 through pipe 94. Hydraulic fluid exhausted from motors 67 through pipe 93 flows to port 110 and through exhaust port 113 to sump 26. Of course, when the core 115 is shifted to the right, the flow of fluid through the valve is reversed with a consequent reversal of operation of the motors 67.

Preferably the inlet or fluid supply conduit for the pump 25 includes a filter 119 and a screen 120 both of which are contained within the sump 26 in which a supply of fluid for operating the motors 67 is stored to such level as to cover the intake screen 120 at all times.

The hydraulic motors 37 and 57 are operated by a hydraulic pump 392 carried in the machinery compartment 15 of the truck 10. The conduits for these motors, like those for the kerf-cutter motors 67, lead through the turnover neck mechanism and are suitably connected with said pump by conduits which connect to individual conduits 45 at the back end of the projecting stub shaft 38 and through the forward wall of the sump casting 39. These conduits are connected, as hereinafter described, by other conduits through a four-unit control valve 448 and other mechanism to pump 392, as disclosed in Patent 2,263,799. The conduits between said valve 448 and the conduits 45 leading to motor 37 are simply flexible conduits having fittings on opposite ends extending therebetween. The close proximity of valve 448 to said conduits 45 is seen by reference to Fig. 6 of the drawings. The interconnecting conduits may be similar in structure to conduit 104 seen in said Fig. 6. The conduits are designated 362 and 363 in Fig. 10 of the drawings.

Attention is now directed particularly to Fig. 10 of the drawings which illustrates diagrammatically the hydraulic control system for operating the mining machine. Said hydraulic system includes a supply tank 380 for hydraulic fluid, preferably oil, from which there extends a feed pipe 381. Feed pipe 381 leads to a control valve 383 that functions to insure that pipe 381 will be under suction at all times and that a pipe 399 will be under pressure at all times regardless of the direction of rotation of pump 392.

Pressure pipe 399 leads to an adjustable volume control and pressure relief valve unit 400 that acts to control the volume and pressure of fluid delivered to the hydraulic system by pump 392. The pressure pipe 409 leads from unit 400 to a two-unit control valve 443 which includes a core for directing hydraulic fluid to operate the turntable motors 19 and a core for directing hydraulic fluid to operate a hydraulic motor 444 which effects slow speed or sumping travel of the truck 10. A pressure conduit 441 connects two-unit control valve 443 to the inlet port of four-unit control valve 448 that is

manually operated to control the operation of hydraulic motors 32, 35, 37 and 57, and an exhaust or drain conduit 449 for returned fluid exhausted by said motors connects the four-unit control valve 448 with tank 380. Motors 32 for pivoting the supplemental frame 21-26 about the axis of pivot shafts 31 are connected to four-unit control valve 448 by conduits 491 and 492, and turnover neck motor 35 is connected to said valve 448 by conduits 503 and 504.

Parts of the turnover neck mechanism 34 are shown in Fig. 10 in a diagrammatic manner and in the present embodiment of my invention turnover neck 34 forms six conduits which lead through and are formed by the co-operating kerf-cutter supporting male and female members 36 and 47 of the turnover neck mechanism. Motor 57 which pivots the cutter head 17 and its associated cutter bar assembly 16 about mounting pins 62 is a double acting piston motor and it is supplied with fluid through conduits 45 which are connected to pipes 364 and 365 that lead from the four-unit control valve 448. The rotary hydraulic motor 37 which swings the cutter bar assembly 16 with respect to the cutter head 17 is connected through conduits 45 which are in turn connected to pipes 362 and 363 that lead from the four-unit control valve 448.

The ports of hydraulic motors 67 are connected by the pipes 93 and 94 which are in turn connected to relatively large conduits 45 that extend through the turnover neck mechanism and ports 110 and 111 of reversing valve 105. Hydraulic fluid under pressure from pump 25 may be directed at will, by reversing valve 105, to either of the pipes 93 or 94 to operate the motors 67 for driving the kerf-cutter chain in either direction.

That portion of the hydraulic mechanism shown to the left of line 126 is identical to the equivalent portion of the hydraulic mechanism and system shown and described in the Jeffrey et al. Patent, 2,263,799, above referred to. The portion of the apparatus shown to the left of line 125 is contained within the machine compartment 45 or carried directly by the truck 10 while all of the mechanism of the hydraulic system to the right of the line 125 is supported by the truck 10 through the motor casing, supplementary frame or support 21-26 of the turnover neck mechanism 34 carried by the turntable 18. The portion of the hydraulic system to the left of line 126 has been described in complete detail in the Jeffrey et al. patent and therefore this portion of the system requires no further explanation here. It is that portion of the system shown to the right of line 126 that is novel with me.

In operation, for transporting the mining machine through a mine the wheels 13 of the truck are driven through a relatively high speed gear mechanism by an electric motor that drives pump 392, neither of which is shown. During the transportation operation the operator of the machine will ride upon a seat at the rear of the truck 10 where he will have ready control of said driving motor and of the hydraulic motors 19 by which he may swing the turntable 18, if necessary, as the mining machine proceeds around sharp corners.

After the mining machine has reached a mine face or position where it is desired to cut a kerf the operator will control the machine from a position adjacent the left side thereof at the 75

rear of the motor casing, supplementary frame, or support 21-26 where operating levers indicated at 127 in Fig. 2 are located.

The electric motor in casing 21 has for its sole purpose the driving of hydraulic pump 25 which in turn operates the kerf-cutter chain driving motor 67. All of the various adjustments to the mining machine are effected by power derived from the electric motor that drives pump 392.

The mining machine is highly versatile in cutting kerfs in any plane by operating the various hydraulic motors hereinbefore described. The mining machine may be operated to start a horizontal kerf, for example, by rotating the turntable 18 to position the axis of the turnover neck mechanism 34 at a right angle with the longitudinal axis of the truck 10 and the cutter bar assembly 16 may be positioned so that its longitudinal axis is parallel to the line of travel of the mining machine. The hydraulic kerf-cutter driving motors 67 are operated, as hereinbefore described, to drive the kerf-cutter chain 76 and with the kerf-cutter chain in operation the mining machine is driven forward at a slow sumping speed by a hydraulic gear train including motor 444 which is connected to drive the wheels 13.

The cutter bar 16 may be sumped or driven into the mine face any distance up to the cutter head frame or housing 62, at which time the operator disconnects the hydraulic sumping drive mechanism, and then to cut a kerf the operator operates the hydraulic motors 19 and 37 to swing the cutter bar assembly 16. When the cut has been completed the machine is backed away from the mine face to withdraw the kerf-cutter bar from the kerf.

The cutter bar may rotate continuously in either direction about the axis of cutter head shaft 72 and it may be caused to cut a kerf, for example, by placing the cutter head housing 62 adjacent the mine face, with the cutter bar 16 parallel to the face and then, through the operation of motor 37, be swung into the mine face to cut a semi-circular kerf.

It is to be understood that the kerf-cutting operations set forth above are but two examples of the many kerf-cutting operations that may be accomplished by the machine.

Both the kerf-cutter bar assembly and the turnover neck mechanism 34 may be rotated in either direction about their respective axes through any number of successive revolutions. Turnover neck mechanism 34 is operated by hydraulic motor 35 which functions to cause the female neck member 47 to be rotated upon the projecting shaft 38. Conduits 45 in shaft 38 are each connected to an individual one of the circumferential grooves 43 and there is a conduit formed by the female neck member 47 for each of conduits 45 in shaft 38. Each of the conduits formed by the female neck member 47 is always in communication with the circumferential groove 43 of its respective conduit 45. Because the conduits 45 are always in communication with their respective conduits in the female neck member 47, the hydraulic motors which are connected to the conduits of the female neck member 47 may be operated in any position of the turnover neck mechanism 34 and while the turnover neck is operated through successive revolutions.

From the foregoing description it will be seen that I have provided a kerf-cutting mining machine wherein a hydraulically powered kerf-cutter head is mounted for universal movement

in cantilever from a support through a turnover neck mechanism. It will also be seen that the supporting turnover neck mechanism forms portions of the hydraulic piping system for conveying hydraulic fluid to and from the hydraulic motors which form a part of and which co-operate with the cutter head for operating it, and that because these portions of the hydraulic system are integral parts of the supporting turnover neck mechanism they will be protected from damage.

With specific reference to the kerf-cutter head mechanism it will be seen that I have provided a kerf-cutter head wherein a kerf-cutting chain is driven directly from hydraulic motors carried by the kerf-cutter head frame and that the hydraulic motors are directly connected to drive the kerf-cutter chain through speed reduction or torque increasing gearing contained within the frame or housing of the kerf-cutter head, and with reference to the speed reducing or torque increasing gearing it will be seen that I have provided an improved connecting gearing for a kerf-cutter head wherein the driving pinions of two motors each mesh with a single large gear to drive it.

While I have described the mining machine as including a wheel supporting vehicle, it is to be understood that, in the broader aspects, the support for the cutter head and turnover neck mechanism need not necessarily be a vehicle, but that it may be any suitable structure, wheeled or otherwise, which may be conveyed within a mine.

Whenever, in any claim, reference is made to "driving" the kerf-cutter or to "driving" the cutter chain, or the equivalent, it is to be understood as restricting said claim to the actual causing of the cutter chain 16 to travel about the cutter bar 17, by rotating sprocket 15, or the equivalent operation and is to be understood as distinguishing from any pivotal swinging of the cutter bar 17 about the axis of shaft 12, or about the axis of turntable 18, or any other swinging or feeding movement thereof which may be involved in a kerf-cutting operation.

Obviously those skilled in the art may make various changes in the details and arrangement of parts without departing from the spirit and scope of the invention as defined by the claims hereto appended and I wish therefore not to be restricted to the precise construction herein disclosed.

Having thus described and shown an embodiment of my invention, what I desire to secure by Letters Patent of the United States is:

1. A mining machine including a main frame, an elongated generally horizontal supplemental frame pivotally mounted on said main frame and having a motor housing at its rear end and a head at its forward end, said supplemental frame forming a cantilever with the motor housing above and attached to said main frame and the

head extending therebeyond, said supplemental frame also including hydraulic conduit forming turnover neck mechanism mounting said head for rotary adjustment upon the axis of said elongated supplemental frame, an electric driving motor in said motor housing at the rear end of said supplemental frame, a pump adjacent and driven by said motor carried by the rear end of said supplemental frame, a kerf cutter mounted on the head at the forward end of said supplemental frame, rotary hydraulic motor means connected to drive said kerf cutter and also mounted on said head, and hydraulic fluid conduits including the conduits formed by said turnover neck interconnecting said hydraulic pump at the rear end of said supplemental frame and the rotary hydraulic motor means at the forward end thereof, said turnover neck conduit mechanism including relatively rotary parts providing continuous conduits while providing for continuous unrestricted rotation of said head relative to the rear end of said supplemental frame on the longitudinal axis thereof.

2. A mining machine including a main frame, an elongated generally horizontal supplemental frame pivotally mounted on said main frame and having a motor housing at its rear end and a head at its forward end, said supplemental frame forming a cantilever with the motor housing above and attached to said main frame and the head extending therebeyond, an electric driving motor in said motor housing at the rear end of said supplemental frame, a pump adjacent and driven by said motor carried by the rear end of said supplemental frame, a kerf cutter mounted on the head at the forward end of said supplemental frame, rotary hydraulic motor means connected to drive said kerf cutter and also mounted on said head, and hydraulic fluid conduits interconnecting said hydraulic pump at the rear end of said supplemental frame and the rotary hydraulic motor means at the forward end thereof.

EDWARD H. STEIN.
